UNITED STATES PATENT OFFICE.

EDWIN COUPLAND SHAW, OF AKRON, OHIO, ASSIGNOR TO THE B. F. GOODRICH COMPANY OF OHIO, OF AKRON, OHIO, A CORPORATION OF OHIO.

VERTICAL VULCANIZING-PRESS.

SPECIFICATION forming part of Letters Patent No. 759,195, dated May 3, 1904.

Original application filed June 17, 1903, Serial No. 161,888. Divided and this application filed October 17, 1903. Serial No. 177,462. (No model.)

To all whom it may concern:

Be it known that I, EDWIN COUPLAND SHAW, a citizen of the United States of America, residing at the city of Akron, county of Summit, and State of Ohio, have invented certain new and useful Improvements in Vertical Vulcanizing-Presses, of which the following is a specification.

This invention relates to an improved vertically-disposed vulcanizing-press adapted more especially for curing annular vehicle-wheel tires by the aid of steam heat as a vulcanizing medium; and the invention has for its object to provide a simple, efficient, and economically-operating apparatus of this character.

The invention includes a vulcanizing-press in which one or more molds holding wheel-tires or other rubber products may be subjected to steam heat or other vulcanizing medium while the molds are held closed by pressure of a ram or follower, which preferably is a fluid-operated ram, compensating change in mass of the rubber stock while it is undergoing vulcanization, thereby assuring constant proper closure of the molds without requiring time-consuming and expensive bolting together of their halves or parts. A series of readily-handled gratings also are preferably interposed between successive molds in the vulcanizing-chamber. These gratings, in connection with the skeleton or perforated form of the ram-head, together with channels provided between ribs or projections formed on the under side of the closed vulcanizer-cover, provide for free circulation of steam or other medium around all parts of the molds to vulcanize their contents evenly, quickly, and economically and also assure a free circulation of water or other cooling medium for quickly cooling the molds after the vulcanization is effected. A crane and piston hoist also are provided for applying and laterally removing the vulcanizer-cover and operate in manner permitting locking and unlocking of the cover while it is suspended by or from the crane-hoist.

The invention will first be described and

then will be particularly defined in claims hereinafter set forth.

Reference is made to the accompanying drawings, forming part of the specification, and in which—

Figure 1 is a central vertical sectional view of my improved vulcanizing-press shown closed and with a series of tire-filled molds and interposed gratings confined between the press-ram and the locked cover of the vulcanizer. Fig. 2 is a detail vertical sectional view showing the press-cover lifted by the crane-hoist prior to swinging the cover to one side by the crane. Fig. 3 is a sectional plan view taken on the line *a a* in Fig. 1 and with the parts appearing as viewed upward in direction of the arrow. Fig. 4 is a detail vertical sectional view taken on the line *b b* in Fig. 1 and illustrates the wedge-locking of the vulcanizer-cover. Fig. 5 is a plan view of portions of a factory building and molding plant, showing the vulcanizer-cover lifted and swung to one side by the crane; and Fig. 6 is a vertical sectional view of parts shown in Fig. 5, with the addition of a stack of molds and interposed gratings resting on the raised press-ram.

The vertical vulcanizer-body 1 is shown supported by its brackets 2 on suitable beams or masonry at the level of a factory-building floor 3 and so that the lower portion of the vulcanizer enters a pit 4 in the floor. On this floor are set up any desired number of mold-preparing tables 5, the tops of which are about level with the open top of the vulcanizer. The vulcanizer and tables are located beneath a track 6, on which run one or more traveling hoists 7, having grapples 8, by which to lift the molds from the tables and convey them to the vulcanizer and also to arrange gratings between the molds, as hereinafter more fully explained.

The vulcanizing-press may be fitted with any approved style of ram or follower adapted to compress rubber-filled molds between it and the closed press-cover. I have specially provided a fluid-operated or hydraulic ram comprising a piston 9, fitted to slide in the

90

95

press-cylinder 10, and preferably having a skeleton or perforated head 11, through which steam or other vulcanizing medium and also water or other mold-cooling medium may have 5 free circulation.

The press-cover 12 has a pendent flange 13, to which are fixed a series of spaced wedge-blocks 14, which are adapted to lock underneath a corresponding spaced series of wedge-blocks 15, fixed to a steel rim or band 16, bolted to the top of the press-body for locking the cover tightly closed and as will be understood from inspection of Figs. 1 and 4 of the drawings. The press-cover is specially 10 provided at its under side with a series of ribs or projections 17, providing between or around them suitable channels 18, through which the heating and cooling mediums may have free circulation next the top of the up- 15 permost mold 19 of a series of molds clamped between the press-ram and the cover, as shown in Fig. 1 of the drawings. I prefer to interpose between the molds 19 suitable gratings 20, each of which is preferably made with an 20 outer metal ring 21 and a series of parallel cross-bars 22, riveted at their ends to the ring and stayed by a central bolt 23, passing through the bars and having spacing-tubes 24, slipped upon it between the cross-bars and as more 25 clearly shown in Fig. 3 of the drawings.

To provide for convenient, easy, and quick bodily removal and replacement of the vulcanizer-cover 12, it is hung at 25 to the rod 26 of the piston 27 of any suitable piston-hoist device 28, which itself is hung by eye-bars or otherwise from the arm 29 of a crane 30, which may turn horizontally on its pivots 31, shown journaled at the floor and ceiling of the factory-building. The crane-arm has 35 proper length to permit swinging by it of the cover 12 directly above the vulcanizer-body 1. The piston 27 may turn in the hoist-cylinder, thus permitting the cover to be turned horizontally in opposite direction by means 40 of hand-bars inserted in its holes 32 to permit locking and unlocking of the cover while it remains connected with or suspended from the crane-hoist. A pipe 29 supplies water, air, or other fluid to the crane-hoist cylinder 45 for operating its piston 27 to raise the vulcanizer-cover 12. A pipe 33 admits water to and permits escape of it from the press-cylinder 10 for operating the ram 9 11. Another pipe 34 admits steam to the press-body 1, to 50 which also a pipe 35 is connected for supply and discharge of water or other medium used for cooling the molds in the press. The press-body also is fitted with the usual steam-gage and thermometer, which it is not necessary to 55 show or describe.

The operation of this improved vertical vulcanizing apparatus is as follows: When the press-cover 12 is raised and swung to one side by the crane-hoist 28 30, as shown in Figs. 5 65 and 6 of the drawings, and after the molds 9

have been filled at the tables 5 with prepared rubber stock adapted to form wheel-tires or other products, the molds are lifted from the tables by the traveling hoist 7 8 and are transferred thereby along the track 6 to the vulcanizing-press and are deposited on the press-ram head 11 in a stack with gratings 20 interposed between them, said gratings being easily and quickly handled by the traveling hoist for lifting them from the factory-floor and placing them upon the molds in the press. The molds and gratings thus may be stacked upon the fully-raised press-ram 9 11, or they may be piled upon the ram as the latter is gradually lowered step by step, the uppermost 70 mold finally resting a little below the level of the open top of the press-body. The crane-hoist 28 30 now is swung around on the pivots 31 to carry the cover 12 over the press-body, whereon it is lowered by the hoist 28 as the piston-raising fluid is allowed to escape through the pipe 29. The cover 12 thus will be lowered until its wedges 14 pass between and below the level of the press-body wedges 15, and the cover now will be turned horizontally by 80 hand-bars inserted in its holes 32 for locking it tightly to the press-body at its packing 36 by engagement of the two sets of wedges 14 15. The press-ram 9 11 now is raised by pressure of water admitted at the pipe 33 to clamp the 85 whole series of molds and interposed gratings between the ram-head 11 and the ribs or projections 17 of the locked press-cover 12, and thereby hold the molds closed. Steam now is admitted to the press-body through the pipe 90 34 and passes through the skeleton ram-head 11, the gratings 20, and the cover-channels 18, whereby very free steam and heat circulation is established around all parts of the molds 19 to effect quick, thorough, and uniform vulcanization of the tires or other rubber products in the molds. When vulcanization is assured, the steam is shut off at the pipe 34, and water or other cooling medium is admitted to the vulcanizer through the pipe 35 to flood and cool the molds. The ram 9 11 now is relieved 100 of fluid-pressure and the water is drained off the molds through the pipe 35, and the press-cover 12 then is turned reversely by the hand-bars a sufficient distance to unlock its wedges 14 from the press-body wedges 15 and carry 105 said wedges out of register, as shown in Fig. 3 of the drawings. Water or compressed air now is admitted through pipe 29 under the crane-hoist piston 27 to lift it and raise the 110 cover 12 clear of the press-body, and the crane is swung back on its pivots 31 to carry it over bodily to one side or to the first-named position. (Shown in Figs. 5 and 6 of the drawings.) The cooled molds and the interposed gratings 115 now are removed from the vulcanizer by the hoist 7 8, by which the molds are returned to the tables 5, where their vulcanized contents are removed to allow cleaning and refilling of the molds with uncured rubber tires or prod- 120 125 130

ucts ready for transferring the molds to the vulcanizer by the hoist 78, substantially as above described.

By this improved vertical vulcanizing-press 5 I am able to vulcanize the contents of a single mold or of any number of molds up to the full mold capacity of the press. Should but a single mold be charged into the press, it will be clamped between the skeleton ram-head 11 10 and the ribs or projections 17 of the press-cover, thus providing as free circulation of steam or heat and of cooling fluid as is assured around two or more clamped molds with one or more gratings interposed between them. 15 The skeleton ram - head, the ribbed press-cover, and the gratings will accommodate molds of varying diameters and form and will always assure free circulation of the vulcanizing and cooling mediums around the mold or 20 molds. By vulcanizing rubber products in two or more molds in one open press-chamber with gratings interposed between the molds I am able to secure more uniformly good results in quick and thorough vulcanization 25 than are possible when a number of molds are clamped directly together in a vulcanizer and without steam and water circulating gratings and ribs or projections providing passages between or next them or when a number 30 of separate steam-heated chambers clamping molds between them are employed.

It will be specially noticed that the compensating pressure of the fluid-operated ram resists counter-pressure arising from change 35 in mass of the rubber stock undergoing vulcanization in the mold or molds, and therefore proper closure of the molds always is assured without recourse to time-consuming and expensive bolting together of their halves or 40 parts. As this compensating pressure is applied to the molds at or over their entire upper and lower areas, there is practically no danger of the molds buckling or bursting under internal pressures arising from expanding 45 or flowing rubber or from the externally-applied pressure of the ram. After the proper pressure per square inch required for any given size or composition of tires or other rubber goods in the molds is calculated and 50 the valve admitting water or fluid to the ram 910 is set to obtain such pressure on the molds the ram automatically adjusts itself to compensate change in mass of the rubber products in the molds during the entire vulcanizing 55 process and without readjusting the valve or any other part of the apparatus.

Various modifications may be made by the skilled mechanic without departing from the spirit of the invention expressed in the ap- 60 pended claims.

I claim as my invention—

1. A vertical vulcanizing-press having a cover bodily removable laterally, and an interior ram or follower formed with a skeleton 65 or perforated head giving fluid circulation

through it and adapted to compress molds between it and the closed cover.

2. A vertical vulcanizing-press having an interior ram or follower and a cover bodily removable laterally and provided at its inner 70 face with ribs or projections forming fluid-passages next a mold clamped to the closed cover by the ram.

3. A vertical vulcanizing-press having an interior ram or follower formed with a skeleton or perforated head giving fluid circulation 75 through it, and a cover bodily removable laterally and provided at its inner face with ribs or projections forming fluid-passages next a mold clamped to the closed cover by the ram. 80

4. A vertical vulcanizing-press having an interior ram or follower and a cover removable laterally, combined with a crane adapted to swing the cover aside bodily to permit top charging and discharging of the press. 85

5. A vertical vulcanizing-press having an interior ram or follower and a cover removable laterally, combined with a crane having a hoist adapted to lift the cover and allow the crane to swing it aside bodily to permit top 90 charging and discharging of the press.

6. A vertical vulcanizing-press having a removable cover which locks and unlocks by horizontal movement, combined with a crane having a hoist provided with a piston coupled 95 to the cover and permitting movement of the suspended cover to lock and unlock it, said crane and hoist being also adapted to lift the unlocked cover and swing it aside bodily to permit top charging and discharging of the 100 press.

7. A vertical vulcanizing-press having an interior ram or follower formed with a skeleton or perforated head giving fluid circulation 105 through it, and a cover removable laterally and provided with inner ribs or projections forming fluid-passages next a mold clamped to the closed cover by the ram, combined with a crane adapted to swing the cover aside bodily to permit top charging and discharg- 110

ing the press.

8. A vertical vulcanizing-press having an interior ram or follower formed with a skeleton or perforated head giving fluid circulation through it, and a cover removable laterally 115 and locking and unlocking by horizontal movement and having inner ribs or projections forming fluid-passages next a mold clamped to the closed cover by the ram, combined with a crane having a hoist provided with a piston 120 coupled to the cover and permitting movement of the suspended cover to lock and unlock it, said crane and hoist being also adapted to lift the unlocked cover and swing it aside bodily to permit top charging and discharg- 125

ing the press.

9. A vertical vulcanizing-press having an interior ram or follower, a bodily-removable cover, and a series of bodily-removable grat- 130

placed in the vulcanizer for compression between the ram and the closed cover.

10. A vertical vulcanizing-press having an interior ram or follower formed with a skeleton 5 ton or perforated head giving fluid circulation through it, a bodily-removable cover, and a series of bodily-removable gratings adapted for interposition between molds placed in the vulcanizer for compression between the ram 10 and the closed cover.

11. A vertical vulcanizing-press having an interior ram or follower, a bodily-removable cover provided with inner ribs or projections forming fluid-passages between or around them, and a series of bodily-removable gratings adapted for interposition between molds placed in the vulcanizer for compression between the ram 15 and the closed cover.

12. A vertical vulcanizing-press having an interior ram or follower formed with a skeleton or perforated head giving fluid circulation through it, a bodily-removable cover provided with inner ribs or projections forming fluid-passages between or around them, and a series of bodily-removable gratings adapted for interposition between molds placed in the vulcanizer for compression between the ram 20 and the closed cover.

13. A vertical vulcanizing-press having a bodily-removable cover and an interior fluid-operated ram adapted to clamp molds between it and the closed cover with a pressure compensating change in mass of the rubber products in the molds during vulcanization.

14. A vertical vulcanizing-press having a bodily-removable cover, and an interior fluid-operated ram having a skeleton or perforated head giving fluid circulation through it and adapted to clamp molds between it and the closed cover with a pressure compensating change in mass of the rubber products in the molds during vulcanization.

15. A vertical vulcanizing-press having a bodily-removable cover provided at its inner face with ribs or projections forming fluid-passages, and an interior fluid-operated ram adapted to clamp molds between it and the closed cover with a pressure compensating change in mass of the rubber products in the molds during vulcanization.

16. A vertical vulcanizing-press having a bodily-removable cover provided at its inner face with ribs or projections forming fluid-passages, and an interior fluid-operated ram 55 having a skeleton or perforated head giving fluid circulation through it and adapted to clamp molds between it and the closed cover with a pressure compensating change in mass of the rubber products in the molds during vulcanization.

17. A vertical vulcanizing-press having a removable cover, an interior fluid-operated ram adapted to clamp molds between it and the closed cover with a pressure compensating change in mass of the rubber products in

the molds during vulcanization, combined with a crane having a hoist adapted to lift the cover and allow the crane to swing it aside bodily to permit top charging and discharging of the press.

18. A vertical vulcanizing-press having a removable cover which locks and unlocks by horizontal movement, and an interior fluid-operated ram adapted to clamp molds between it and the closed cover with a pressure compensating change in mass of the rubber products in the molds during vulcanization, combined with a crane having a hoist provided with a piston coupled to the cover and permitting movement of the suspended cover to 75 lock and unlock it, said cover and hoist being also adapted to lift the unlocked cover and swing it aside bodily to permit top charging and discharging of the press.

19. A vertical vulcanizing-press having a bodily-removable cover, an interior fluid-operated ram adapted to clamp molds between it and the closed cover with a pressure compensating change in mass of the rubber products in the molds during vulcanization, and a series of bodily-removable gratings adapted for interposition between molds placed in the vulcanizer.

20. A vertical vulcanizing-press having a bodily-removable cover, an interior fluid-operated ram having a skeleton or perforated head giving fluid circulation through it and adapted to clamp molds between it and the closed cover with a pressure compensating change in mass of the rubber products in the molds during vulcanization, and a series of bodily-removable gratings adapted for interposition between molds placed in the vulcanizer.

21. A vertical vulcanizing-press having a bodily-removable cover provided at its inner face with ribs or projections forming fluid-passages, an interior fluid-operated ram adapted to clamp molds between it and the closed cover with a pressure compensating change in mass of the rubber products in the molds during vulcanization, and a series of bodily-removable gratings adapted for interposition between molds placed in the vulcanizer.

22. A vertical vulcanizing-press having a bodily-removable cover provided at its inner face with ribs or projections forming fluid-passages, an interior fluid-operated ram having a skeleton or perforated head giving fluid circulation through it and adapted to clamp molds between it and the closed cover with a pressure-compensating change in mass of the rubber products in the molds during vulcanization, and a series of bodily-removable gratings adapted for interposition between molds placed in the vulcanizer.

23. A vertical vulcanizing-press having a removable cover, an interior fluid-operated ram adapted to clamp molds between it and the closed cover with a pressure compensating

change in mass of the rubber products in the molds during vulcanization, and a series of gratings adapted for interposition between molds placed in the vulcanizer, combined with 5 a crane having a hoist adapted to lift the cover and allow the crane to swing it aside bodily to permit top charging and discharging of the press.

24. A vertical vulcanizing-press having a 10 removable cover which locks and unlocks by horizontal movement, an interior fluid-operated ram adapted to clamp molds between it and the closed cover with a pressure compensating change in mass of the rubber products

in the molds during vulcanization, and a series of gratings adapted for interposition between molds placed in the vulcanizer, combined with a crane having a hoist provided with a piston coupled to the cover and permitting movement of the suspended cover to 15 lock and unlock it, said crane and hoist being also adapted to lift the unlocked cover and swing it aside bodily to permit top charging and discharging of the press.
